Attorney.

UNITED STATES PATENT OFFICE.

JESSE H. RICHARDSON, OF PHILADELPHIA, PENNSYLVANIA.

SAFETY-CHUCK.

1,211,758.

Specification of Letters Patent.

Patented Jan. 9, 1917.

Application filed August 5, 1915. Serial No. 43,737.

To all whom it may concern:

Be it known that I, JESSE H. RICHARDSON, a citizen of the United States, residing in the city of Philadelphia, county of Philadelphia, 5 and State of Pennsylvania, have invented certain Improvements in Safety-Chucks, of which the following is a specification.

My invention relates to a safety chuck designed more particularly for operating drills 10 and reamers, and its primary object is to provide an improved device for protecting operators of drill presses and reaming gauntrees.

The improvements are characterized by 15 simple, certain and efficient locking and unlocking means adapted to be automatically engaged by the engagement of the tool with the work and automatically disengaged when the tool feed is off or the tool is not subject 20 to the resistance of the work, so that the chuck, together with the tool, will be stopped upon encountering slight resistance, an engagement with an operator's clothing stopping these parts and protecting him from 25 the injuries that frequently occur to operators as a result of their sleeves being wound up when caught.

The improvements effect the further desideratum of preventing the disengagement 30 of the chuck and the tool running ahead of the feed when the helical cutting edge makes a working engagement that tends to draw the tool forward.

The characteristic advantages of the invention will more fully appear from the following description and the accompanying drawings of a preferred form thereof.

In the drawings, Figure 1 is a part sectional elevation of mechanism embodying 40 my improvements; Fig. 2 is an enlarged sectional view of details of the construction shown in Fig. 1; Fig. 3 is a further sectional view of the details of Fig. 2 shown in different relation; Fig. 4 is an enlarged bottom 45 plan view of the base of the driving shank shown in Fig. 1; and Fig. 5 is an enlarged sectional view taken on the line 5—5 of Fig. 1.

The mechanism illustrated comprises the 50 driving shank 1 (adapted to be engaged in a drill press or reaming gauntree) having the circular base 2, provided with the male thread 3, the jaws 4 containing the springs 5, and the axial socket 6 with relation to 55 which the jaws are symmetrically disposed.

A cylindrical sleeve 6' is provided with the female thread 7 within its top which is adapted to engage the thread 3, whereby the shank 1 carries the sleeve, the sleeve containing the circular interior race 8 intermediate its length for the antifriction balls 9 and having fixed on the lower end thereof the collar 10 containing the circular race 11 for the antifriction balls 12.

The cylindrical chuck head 13, having 65 jaws 14 complementary to the jaws 4, is disposed in the sleeve 6' where it is revoluble in contact with the balls 8, which guide it by contact with the periphery of its cylindrical body, and the balls 12 which support 70 it through their engagement with the plane surface 15. A cylindrical stem 16 on the top of the head 13 enters the socket 6 in freely movable relation and a cylindrical stem or neck 17 on the lower end of the body extends 75 through the collar 10, the neck 17 containing a threaded axial socket 18 therein. A bearing ring 19 of soft metal surrounds the neck 17 within the collar 10 to which it is fixed, 80 the top of the ring serving as a retainer for 80 the balls 12.

The chuck 20 has on the neck or stem 21 at its top a threaded stud 22 which is engaged in the socket 18, whereby the chuck 25 and the bit or tool 23 engaged therein are 85 revoluble by the head.

The shank 1 is revoluble independently of the connected head 13, chuck 20 and tool 23 excepting when, by an upward thrust on the tool or its engagement by the work, the forwardly feeding shank effects the engagement of its jaws 4 with the jaws 14, by the entry of the tooth 4^a of square cross section into the notch 14^b of like cross section and the entry of the tooth 14^a of square cross section 95 into the notch 4^b of like cross section against the actions of the coiled springs 5, which extend transversely to the axis of revolution and normally into the notches 4^b. This engagement will be maintained as the shank 100 is fed forward with the tool in engagement with the work, even in such cases as when the helical fluting of the tool is engaged by a projection of the work which tends to feed the tool forward faster than the feed of the 105 machine, for the square engagement between the jaws maintains the locked relation so long as there is resistance to the rotary movement of the tool. But when the resistance to the rotary movement of the tool has 110

been eliminated, as where the drill or reamer has passed through the work, the springs 5 expand and press against the jaws 14 which are thereby disengaged from the jaws 4 and 5 the parts 13, 20 and 23 are moved longitudinally or drop down by gravity the distance permitted by the controlling devices 6' and 13, so that the jaws 14 clear the jaws 4, in 10 which relation, whether before the tool engages the work or after it has passed through, slight resistance to the spinning of the parts 13, 20 and 23 will stop them.

Having described my invention, I claim:

1. In an instrument of the character described, revolute driving means provided with a locking device and a controlling device, in combination with revolute driven means provided with a locking device adapted to be engaged by said locking device first 15 named, means for turning said driving means to effect the disengagement thereof from said locking device and a controlling device coacting with said controlling device first named, whereby said means second 20 named are permitted a limited longitudinal movement relative to said means first named and said means first named are adapted to revolve independently of said means second named.
2. In an instrument of the character described, revolute driving means provided with a locking device adapted for positive engagement and a controlling device, in combination with revolute driven means provided with a locking device adapted to be engaged positively by said locking device first named and a controlling device coacting with said controlling device first named, anti-friction bearings whereby said means 25 40 are journaled relatively, said means second named being permitted a limited longitudinal movement relative to said means first named and said means first named being adapted to revolve independently of said means second named, and a spring for disengaging said locking devices.
3. In an instrument of the character described, a shank having connected therewith a sleeve and a clutching device, in combination with a chuck provided with a head having a clutching device movable in said sleeve into engagement with said clutching device first named, said devices comprising means whereby when engaged said shank and chuck 45 50 55 are by the revolution of said shank locked together against relative longitudinal movement.
4. In an instrument of the character described, a driving shank comprising one or 60 more jaws and a sleeve having a cylindrical interior surface concentric with said shank, in combination with a chuck provided with a cylindrical head having a limited longitudinal movement in said sleeve and one or more 65 jaws adapted for engaging said jaw or jaws

first named, and means for automatically turning said head to effect the separation of the engaging jaws.

5. In an instrument of the character described, a revolute shank provided with 70 jaws having a bearing surface substantially at right angles to the axis of said shank and a sleeve having a cylindrical interior surface surrounding said jaws, said surfaces and jaws being concentric with said shank, in 75 combination with a chuck provided with a cylindrical head having a limited longitudinal movement in said sleeve and jaws on said head having bearing surfaces disposed substantially at right angles to the axis of 80 said shank and adapted for engaging said bearing surfaces first named.

6. In an instrument of the character described, a revolute shank provided with 85 jaws having a bearing surface substantially at right angles to the axis of said shank, and a sleeve having a cylindrical interior surface surrounding said jaws, said surface and jaws being concentric with said shank, in combination with a chuck provided with a cylindrical head having a limited longitudinal movement in said sleeve and jaws on said head having bearing surfaces disposed substantially at right angles to the axis of 90 said shank and adapted for engaging said bearing surfaces first named, and one or more 95 springs for disengaging said jaws.

7. In an instrument of the character described, a revolute shank provided with a sleeve, a jaw fixed within said sleeve, a chuck 100 provided with a head revolute and longitudinally movable in said sleeve, a jaw fixed to said head and adapted to engage said jaw first named, and a spring for turning said head to effect the disengagement of said jaws. 105

8. In an instrument of the character described, a revolute shank having concentric jaws provided with bearings disposed transversely to the axis thereof, in combination with a revolute device provided with concentric jaws having bearing surfaces disposed transversely to its axis and adapted for engaging said jaws first named in locking relation, means comprising anti-friction bearings whereby said chuck is permitted a 11 limited longitudinal movement relative to said shank and said shank is permitted to revolve independently of said device, and a spring for turning said device to effect the disengagement of said jaws. 115

9. In an instrument of the character described, a revolute shank having concentric jaws and a sleeve having a concentric cylindrical interior surface, said sleeve provided with a collar thereon concentric with said 12 surface, in combination with a chuck having a head with a cylindrical surface disposed in said sleeve and jaws on said head adapted for engaging said jaws first named, anti-friction balls disposed between said cylindri- 13

cal surfaces, and anti-friction balls carried by said collar to provide bearings for said head, said head being movable longitudinally and revolvably in said sleeve.

5 10. In an instrument of the character described, a shank provided with a tooth and a notch, a sleeve fixed to said shank, a chuck provided with a head adapted to revolve and reciprocate axially in said sleeve, said head

provided with a tooth adapted to be engaged in said notch and a notch adapted to receive said first named tooth, and means whereby said teeth are automatically disengaged from said notches.

In testimony whereof I have hereunto set 15 my name this 31st day of July, 1915.

JESSE H. RICHARDSON.
